UNITED STATES PATENT OFFICE

GEORGE ANDRESEN, OF CHICAGO, ILLINOIS, ASSIGNOR TO W. B. PARKYN, OF CHICAGO,
ILLINOIS

REFRIGERATING APPARATUS

Application filed April 25, 1927. Serial No. 186,311.

My invention relates more particularly to refrigerating apparatus of the so-called flooded type in which the evaporator element, as for example a coil, is filled at all times with the liquefied refrigerating agent supplied thereto under the control of any suitable means, as for example a float-controlled valve, located in a receptacle in communication with the coil and into which the liquid-refrigerant supply pipe opens.

In such systems where the gas in liquefied condition is heavier than the lubricating oil supplied to the compressor, the oil accumulates in the float chamber referred to forming a layer on the upper surface of the body of liquefied refrigerant therein, and presenting great objections in structures as hitherto provided, as is well understood in the art, due to the fact that the refrigerant which becomes gasified in performing the refrigerating function, is required to pass upwardly, in gaseous form, through the layer of oil referred to, in its travel back to the compressor for recompression and liquefaction and subsequent discharge to the evaporator coils, the oil layer referred to blanketing the free flow of the gas to the inlet of the compressor and interfering with the desired maximum functioning of the machine.

My object is to provide a construction by which the passage of the gasified refrigerant through the oil layer referred to, in its travel to the inlet of the compressor, will be obviated and thereby overcome the objections incident to the requirement that the gasified refrigerant pass through such layer.

Referring to the accompanying drawings:—

Figure 1 is a view in vertical sectional elevation of an evaporator element of the so-called flooded type in which my invention is incorporated. Figure 2 is a section taken at the line 2 on Fig. 1 and viewed in the direction of the arrow; and Figure 3, a view somewhat diagrammatic, of a refrigerating system in which my improved evaporator element is incorporated.

As a preface to the following description of the illustrated construction, it may be stated that my invention consists primarily in pro-

viding a conduit which opens into the body of liquefied refrigerant below the layer of oil thereon and through which the gasified refrigerant is conducted to the point of discharge, thereby avoiding the necessity of drawing the gas through the layer.

In the accompanying drawings I have shown my invention as applied to a refrigerating system employing an evaporator element of the flooded-type and of common construction and comprising a receptacle 3 opening into the upper ends of a series of U-pipes 4 which would be located in a refrigerating brine-tank, or extend into a space to be refrigerated. The receptacle 3 forms a float-chamber into which opens a pipe 5 which in practice would lead from any suitable source of liquefied refrigerant which in liquefied condition is heavier than the lubricating oil used in the compressor, as for example from a condenser, such as that shown at 100, to which the compressed gasified refrigerant is supplied from a compressor, as for example that shown at 101, the inlet of which is in communication with the upper portion of the receptacle 3. The receptacle 3 is provided with a valve 6 for controlling the flow of the liquefied refrigerant from the pipe 5 into the receptacle 3, this valve being controllable, by a float-device 7 for maintaining in the receptacle 3 and pipes 4 the desired depth of body of liquefied refrigerant. The outlet from the receptacle 3 for the refrigerant which becomes gasified in the pipes 4 in performing the refrigerating function, and through which the gasified refrigerant is conducted to the compressor 101 for compressing the gasified refrigerant, is represented at 8, this pipe opening into the upper portion of the receptacle 3 above the level of the liquefied gas therein.

In accordance with the particular illustrated embodiment of my invention, I provide in the receptacle 3 a pair of vertically extending pipes 9, each shown as a segment of an annulus and open at opposite ends and secured to the inner surface of the receptacle 3 at opposite sides of the latter the lower ends of these pipes, which form by-passes, opening into the receptacle 3 at a point below the

horizontal plane of the oil layer referred to and represented diagrammatically at 10, and the upper ends of these pipes opening above said layer and preferably above the inlet of 5 the pipe 8, the pipes 9 being of such length that they will occupy the respective positions stated relative to the oil layer 10, regardless of variations in the height at which such layer extends.

- 10 In the operation of the apparatus the refrigerant, which becomes gasified in the pipes 4 in the refrigerating operation, rises through the open ends of these pipes into the liquid refrigerant in the receptacle 3 and enters the 15 lower ends of the pipes 9 through which it passes upwardly and discharges at the open ends thereof into the receptacle 3 above the oil layer 10 therein and thence passes, together with such of the oil as overflows into 20 the pipe 8 when the oil level reaches this point, into the pipe 8 and into the inlet of the compressor, under the suction action of the latter, the gas thus passing around, instead of through, the oil layer 10, with the manifest 25 advantage.

The by-pass arrangement shown provides sufficient passage of the gas from the bath into the space above the bath as to approximately equalize the pressure above and below 30 the oil blanket thereby causing the device to function to overcome the disadvantages resulting from the blanketing of the oil.

In the discharge of the oil and liquefied refrigerant into the chamber 3 such separation 35 takes place that all except possibly a very small proportion of the oil rises and forms the blanket, this small proportion only passing into the pipes 4. Defined in another way, only such oil as is taken up by the refrigerant 40 due to the mutual solubility of these liquids, passes into the pipes 4. While it is possible that some oil will be found on the top of the liquefied refrigerant in the pipes 9, a relatively thin film only of this oil would exist as 45 compared with the relatively heavy blanket of oil on the bath in the chamber 3, but such oil is quickly discharged through the outlets of the pipes 9 under the boiling action of the refrigerant in performing the refrigerating 50 function and the pipes are thus rendered self-cleaning of oil. Thus there is no possibility of the building up on the top of the refrigerant in the pipes 9, of a blanket such as is built up in the chamber 3.

55 While I have illustrated and described a particular construction embodying my invention, I do not wish to be understood as intending to limit it thereto, as the same may be variously modified and altered without departing from the spirit of the invention, and as a suggestion of one of the various modifications which may be made in the structure shown, it may be stated that, if desired, 60 one of the pipes 9 may be omitted.

What I claim as new, and desire to secure by Letters Patent, is:

1. In refrigerating apparatus employing a refrigerating medium which in liquid state is heavier than the oil which becomes mixed therewith in the operation of the compressor, means for compressing a refrigerant in gaseous condition and liquefying the compressed refrigerant, an evaporator element, means for supplying the refrigerant in liquefied condition from said first-named means to said element and maintaining a body thereof in said element, and means in communication with the body of liquefied refrigerant below the layer of oil thereon for conducting away 70 from said body and into said element above the layer of oil the refrigerant gasified in said body, said element having an outlet between the body of liquefied refrigerant and the point at which said third named means opens 75 into said element above the oil. 80

2. In refrigerating apparatus employing a refrigerating medium which in liquid state is heavier than the oil which becomes mixed therewith in the operation of the compressor, 90 means for compressing a refrigerant in gaseous condition and liquefying the compressed refrigerant, an evaporator element, means for supplying the refrigerant in liquefied condition from said first-named means to said 95 element and maintaining a body thereof in said element, and means in communication with the body of liquefied refrigerant below the layer of oil thereon for conducting away from said body into the upper portion of 100 said element the gas evaporated from said body, said element containing an outlet in communication with said first-named means and located between the body of liquefied gas and the point at which said third-named means 105 opens into said element above said body. 110

3. In refrigerating apparatus employing a refrigerating medium which in liquid state is heavier than the oil which becomes mixed 115 therewith in the operation of the compressor, means for compressing a refrigerant in gaseous condition and liquefying the compressed refrigerant, an evaporator element, means for supplying the refrigerant in liquefied condition from said first-named means to 120 said element and maintaining a body thereof in said element, and a conduit in communication with the body of liquefied refrigerant below the layer of oil thereon for conducting away from said body and into said element above the layer of oil the refrigerant gasified in 125 said body, said element having an outlet between the body of liquefied refrigerant and the point at which said third named means opens into said element above the oil. 130

4. In a gas-liquefying apparatus, the combination of a receptacle, an evaporator coil in communication therewith, means for maintaining in said receptacle and coil a supply

of liquefied gas on which floats a layer of oil, and means for conducting away from said receptacle gas generated in said body of liquefied gas comprising a conduit opening at one end only into the body of liquefied gas 5 below the oil layer thereon and at its opposite end above the level of the liquefied gas and lubricant and through which conduit the gas passes, said element having an outlet disposed above the top of the body of liquefied gas.

5. In a gas-liquefying apparatus, the combination of a receptacle, an evaporator coil located below said receptacle and in communication therewith, means for maintaining in said receptacle and coil a supply of liquefied gas on which floats a layer of oil, and means for conducting away from said receptacle gas generated in said body of liquefied gas comprising a pipe opening at its upper end into said receptacle above said layer and at its lower end into the body of liquefied gas below the oil layer thereon, and a conduit leading away from the receptacle above the liquid therein.

6. In a refrigerating apparatus employing a refrigerating medium which in liquid state is heavier than the oil which becomes mixed therewith in the operation of the compressor 15 for compressing the gasified refrigerating medium, means for compressing the refrigerant in gasified condition and liquefying the compressed refrigerant, a receptacle, an evaporator coil located below said receptacle and 20 in communication therewith, means for supplying the refrigerating medium in liquefied condition from said first-named means to said receptacle and maintaining a body thereof in said receptacle and coil, and means for returning to said compressor the refrigerant 25 gasified in said coil comprising a conduit opening at one end only into the body of liquefied refrigerant below the layer of oil thereon through which the gas passes in its 30 passage to the compressor, said element having an outlet disposed above the top of the body of liquefied refrigerant.

7. In a refrigerating apparatus employing a refrigerating medium which in liquefied state is heavier than the oil which becomes mixed therewith in the operation of the compressor for compressing the gasified refrigerating medium, means for compressing the refrigerant in gasified condition and liquefying the compressed refrigerant, a receptacle, an evaporator coil located below said receptacle and in communication therewith, means for supplying the refrigerant in liquefied condition from said first-named means to said 50 receptacle and maintaining a body thereof in said receptacle and coil, and means for returning to said compressor the refrigerant gasified in said coil comprising a conduit opening at one end into the body of liquefied refrigerant below the layer of oil thereon 55

and at its upper end into said receptacle above said layer, and a conduit opening into said receptacle above said layer and through which the gasified refrigerant passes to said compressor.

8. In a gas-liquefying apparatus, the combination of an evaporator element to which liquefied gas heavier than oil and mixed therewith is supplied, means for defining the level of the liquid in said element, and means providing a gas-passage extending from below the top of the body of liquefied gas to a point above the top of the body of oil thereon for conducting away from the body of liquefied gas in said element the gas evaporated therefrom.

9. In a gas-liquefying apparatus, the combination of an evaporator element to which liquefied gas heavier than oil and mixed therewith is supplied, means for defining the level of the liquid in said element and means providing a gas-passage extending from below the top of the body of liquefied gas to a point in said element above the top of the body of oil on said body of liquefied gas for conducting away from the body of liquefied gas in said element the gas evaporated therefrom, said element containing an outlet located between the body of liquefied gas and the point at which said gas-passage opens into said element above said body.

10. In a gas-liquefying apparatus, the combination of an evaporator element to which liquefied gas heavier than oil and mixed therewith is supplied, means for defining the height to which liquefied gas extends in said element, means defining the height to which oil superposed on the body of liquefied gas extends and forming an outlet for said oil, and means providing a gas-passage extending from below the top of the body of oil thereon, for conducting away from the body of liquefied gas in said element the gas evaporated therefrom.

11. In a gas-liquefying apparatus, the combination of an evaporator element to which liquefied gas heavier than oil and mixed therewith is supplied, means defining the level of the liquid in said element, and a by-pass for conducting the gasified refrigerant from the body thereof so disposed as to avoid subjection of the gas-flow to impedance by the layer of oil.

12. An evaporator including a header, evaporator pipes depending therefrom, internal pipes extending from the bottom of the header near the evaporator pipes to the top of the header.

13. The method of evaporating liquid refrigerant, covered by a layer of oil, in the production of refrigerating temperatures, which consists in conducting the gas evaporated from the body of refrigerant away from the body thereof through a course such that

the gas-flow is not subject to impedance by the layer of oil.

14. The method of evaporating liquid refrigerant, covered by a layer of oil, in the production of refrigerating temperatures which consists in by-passing the gas evaporated from the body of refrigerant around the layer of oil to avoid overcoming, by the gas-flow, of impedance by the layer of oil.
15. The method of evaporating liquid refrigerant, covered by a layer of oil, in the production of refrigerating temperatures which consists in conducting the gas evaporated from the body of refrigerant away from the body thereof to a point above the layer of oil without the necessity of overcoming the surface tension of the oil.

GEORGE ANDRESEN.
